INTERMITTENT POSITIVE PRESSURE BREATHING APPARATUS

Larry O. Murphy, Bountiful, Utah, assignor to
Sandoz, Inc., East Hanover, N.J.

Filed May 25, 1973, Ser. No. 364,123

Term of patent 14 years

Int. Cl. D24—01

U.S. Cl. D83—1 N

FIG. 1

FIG. 2

FIG. 3

FIG. 4

FIG. 5

FIG. 6

FIG. 1 is a top plan view of an intermittent positive pressure breathing apparatus showing my new design;

FIG. 2 is a side elevational view thereof;

FIG. 3 is an end elevational view thereof;

FIG. 4 is a side elevational view thereof opposite to that shown in FIG. 2;

FIG. 5 is an end elevational view thereof opposite to that shown in FIG. 3; and

FIG. 6 is an isometric view thereof.

I claim:

The ornamental design for an intermittent positive pressure breathing apparatus, as shown.
